(57) **CLAIM**

The ornamental design for a rear bumper of an automotive vehicle body, as shown and described.

DESCRIPTION

FIG. 1 is a top, front and right side perspective view of a rear bumper of an automotive vehicle body;

FIG. 2 is a left side elevational view thereof;

FIG. 3 is a right side elevational view thereof;

FIG. 4 is a rear elevational view thereof;

FIG. 5 is a front elevational view thereof;

FIG. 6 is a top plan view thereof; and,

FIG. 7 is a bottom plan view thereof.

The broken lines of even length depict portions of the automotive vehicle body that form no part of the claimed design.

The portions of the automotive vehicle body shown in broken lines throughout the drawing views are for illustrative and environmental purposes that form no part of the claimed design.
